INVENTOR.

BY *Waldo M. Chapin*
ATTORNEY

UNITED STATES PATENT OFFICE

JULIUS FRIED, OF NEW YORK, N. Y.

CONTAINER AND APPLICATOR

Application filed July 29, 1932. Serial No. 625,714.

This invention relates to a combined container and applicator adapted to hold and dispense medicinal liquid preparations in minute quantities for direct local application.

The solutions for which said device can advantageously be employed comprise antisepsics, like iodine, mercurochrome, peroxide, potassium permanganate, carbolic acid, etc., or it may be a cautery like a silver nitrate solution and similar chemicals which easily would stain the hands of the operator or other objects if too copiously dispensed. The device is also very useful to contain highly volatile liquids like sulphuric ether or a solution of collodion, or hygroscopic or efflorescent liquids. It is obvious, however, that a practical application of my combined container and applicator is not necessarily confined to medicinal or sanitary purposes only, but that its peculiar advantages may be realized also for other and diverse purposes, for example to apply perfume in discrete quantities to objects, or to apply stain removing media, like benzene, carbon-tetrachloride, Javelle water, ink eradicators, etc., to a limited area or the like, and such and similar applications, therefore, would fall within the scope of my claims.

The first and main purpose of my invention, however, is to provide a combined bottle and applicator which above all other features can be kept surgically clean.

A second object, concurrent with the first one, is to provide a container which does not need to be closed by a cork or stopper inserted into the dispensing orifice, as such corks or plugs can easily transplant germs from the outside by direct contact and conveyance into the container.

A third object is to provide a sanitary container which despite the just mentioned absence of an inserted plug or cork, can, nevertheless, be closed airtight so that no contamination by dust, germs or bacteria from the outside can reach the contents while the device is stored away.

A fourth object is to provide an applicator which needs no dipping or applicator rod which often is liable to transfer dust or cot-

ton lint or even shreds from bandages or wounds into the interior of the container.

A fifth object subservient to the last named is to provide an applicator which is directly applied to the spot to be medicated whereupon it may be sterilized by any convenient method while still in the inverted position.

A sixth object concurrent with the objects just mentioned, is an applicator which immediately before and after use may be sterilized by drawing the apertured end of it through a flame.

A seventh object is to provide a container which on account of its peculiar construction, offers a fair guarantee against refilling and therewith against adulteration of its original contents.

An eighth object is to provide a container which due to its above mentioned special construction, prevents accidental spilling or waste of the contents.

A ninth object, is to provide an applicator which must directly touch the spot to be medicated before it dispenses its liquid contents.

A tenth object is to provide an applicator which when used will release the medicating or active fluid only in drops or restricted quantities, guaranteeing, therefore, an economical application and prevention of waste.

Other objects encompassed by or concurrent with the above, will become obvious from the more detailed description and illustration by the attached drawing in which:

Figure 1 is an elevation, partly in section of a combined container and applicator, made according to the principles of my invention.

Figure 2 is a similar elevational view, also partly in section, illustrating a modified form of the invention.

Figure 3 is a cross sectional view taken on line 3-3 of Figure 2 at an enlarged scale.

Figure 4 is an elevational cross section through a cap for the applicator tip, showing at the same time a form modified from the former ones. The figure is also drawn on an enlarged scale.

Similar characters denote similar parts throughout the different views.

Referring more in detail to the illustra-

tions shown, 10 designates the main body of the container. This has preferably the general form of a small bottle or flask, having an elongated conical neck 11 with a moderate contraction 12 beneath it.

5 Modifications of this general form, however, are entirely within the compass of the invention. For instance, a device of the character described and destined for a chemical 10 or bacteriological laboratory may in its lower portion conveniently have the diameter and general shape of a test tube so that it can be stored away on a rack adapted to hold test tubes. Or if the device is adapted for 15 use as a toilet article or ladies' boudoir, it may have any desired ornamental shape, as far as its main body is concerned. Also, the material of which it is made, may vary a great deal, according to the purpose, price, 20 etc. It may be made of glass, wood or metal, especially such material which is not attacked by or does not enter into chemical combination with the fluid contents, (for example a lead flask would be suitable for fluo- 25 ric acid, used for glass etching); porcelain, fibre, hard rubber or a cellulose or phenol condensation product may also be used, in fact any suitable and incompressible substance may be employed.

30 The conical neck is drawn out to a rounded-off tip 13 with a small hole 14 in it. This aperture must be of such minute size, that the fluid contents under ordinary barometric pressure do not run out spontaneously by 35 gravity when the bottle or container is reversed, but are held back within the container by capillary attraction. Yet, the size of the opening will be slightly greater for fluids having greater viscosity in proportion to this 40 quality. When, however, the tip of the conical neck, which serves as an applicator, is dabbed upon or rubbed over a surface, the liquid will be drawn from the container by adhesion and will continue to flow out in 45 a scanty driblet as long as the rubbing contact is kept up.

The bottle is originally filled by any convenient method known to those skilled in the art, preferably by the vacuum method, but 50 as no special claim is made regarding the method of original filling, this is not described in detail. It is, however, clear that the container when empty cannot be refilled like an ordinary bottle and also that, while in 55 use, it cannot very well be tampered with in thinning or adulterating the contents, unless a special apparatus for fraudulent purposes is employed.

60 It is furthermore evident that all other objects listed in the premises are fulfilled in an efficient and inexpensive way. If the applicator be made of glass or even metal or porcelain, it may be sterilized by drawing through a flame.

65 How the third mentioned object is at-

tained, however, remains to be described hereafter.

As shown in Figure 1, a cap 16 is provided which tightly fits the conical neck 11 of the applicator by a conical recess 17. If both, the cap and the applicator, are made of glass, they should advantageously be ground to an airtight fit. The interior of the cap, however, leaves a clearance 18 over the applicator tip which is essential, first in order to leave the orifice uncontaminated and secondly to prevent any adhering drop at the tip end to dry into an adhesive sticky substance and thus to hinder the easy removal of the cap. The upper end of the cap may be formed as a sphere or globe 19 to facilitate handling the cap. Figure 4 shows a modification of the cap construction inasmuch as a threaded connection 20 between cap and applicator is provided which makes the locking 25 of the cap still more secure. In addition, the cap may be ground or cast in such relation to the applicator that when the ultimate end 20a of the conical thread 20 is engaged, the inner mantle 17a of the cap just 30 fits the conical outer surface 11a of the applicator.

In the modified construction, illustrated in Figure 2, the same elements as described in connection with Figure 1 are provided. In 35 addition thereto, the tip of the applicator is beaded, i. e. the conical surface just below the rounded off end is contracted as shown at 21 and the cap which is made in the form of a thimble, closely fitting over the conical neck 100 of the applicator, has a corresponding contraction 22 which may resiliently be slipped over the beaded tip so as to lock the mouth of the container against the outer atmosphere. This beaded extremity or applicator 105 may be hollow, as shown in Figure 2, or it may be a solid bead with the hole drilled through it.

Another feasible modification of the applicator shape which would prove especially 110 handy in dental work, for instance for the local application of cocaine, would consist in a curved elongation of the neck (not shown) so that one could apply the tip to narrow and confined places.

115 While only two preferred forms of execution of the invention are shown, it is, however, to be understood that the invention is not confined to these forms and that the drawing, therefore, is to be considered as illustrative only, not as restrictive, and that many modifications and changes are possible without deviating from the general principles of the invention. The scope of the invention, therefore, should be judged rather by the 120 following claim.

I claim:

125 A combined liquid container and applicator having a single restricted normally open orifice adapted to retain the liquid contents 130

by capillary attraction and barometric pressure when the container is inverted and to permit a slow discharge of the liquid by adhesion when said orifice is brought into
5 contact with a surface underneath.

In testimony whereof I affix my signature.

JULIUS FRIED.
